UNITED STATES PATENT OFFICE.

WILLIAM RICHARDSON, OF MILWAUKEE, WISCONSIN, ASSIGNOR TO THE MILWAUKEE DUST COLLECTOR MANUFACTURING COMPANY, OF SAME PLACE.

DUST-COLLECTOR.

SPECIFICATION forming part of Letters Patent No. 299,852, dated June 3, 1884.

Application filed February 25, 1884. (No model.)

To all whom it may concern:

Be it known that I, WILLIAM RICHARDSON, of Milwaukee, in the county of Milwaukee, and in the State of Wisconsin, have invented certain new and useful Improvements in Dust-Collectors; and I do hereby declare that the following is a full, clear, and exact description thereof.

My invention relates to improvements in dust-collectors, and will be fully described and claimed hereinafter.

In the drawings, Figure 1 is a partly broken end view of the dust-collector. Fig. 2 is a broken vertical section of the same, and Fig. 15 3 shows in vertical cross-section a portion of the balloon.

The object of my invention is to provide means whereby certain working parts of a well-known form of dust-collector are kept in close and air-tight-fitting adjustment, in order to properly operate. This dust-collector, which forms the subject of Letters Patent Nos. 272,473 and 272,474, granted to Faustin Prinz, February 20, 1883, has a balloon, B, revolving in a casing, A. In the machine as heretofore constructed this balloon is provided around the edge of its centrally-opened head with a ring, which bears on the inner face of a similarly-shaped ring fastened around the edge of the opening of the casing. As this arrangement fails to exclude the air from the space between the balloon and the casing, I substitute the improved rings C D E, as shown in Fig. 2 of the drawings. The ring C is simply a band 35 of hoop-iron squarely fastened around the inner edge of the opening in the casing A. Inside this ring C is a double-L-shaped ring, D, the inner L of which embraces the outer face and inner edge of the central opening in the 40 head b of the balloon B, in which it is fastened, while the outer L sets freely against the inner face of the ring C and the outer face of the casing A. The outer part of the ring D is extended outward to form a concave molding, wherein is folded the inner edge of the ring F, of felt, rubber, or other suitable flexible material. The outer rim of this felt ring is laid flat against the outer face of the casing

A, and is kept in place by screws, which also serve to fasten the outer bearing-ring, E, to the same. This outer ring, E, has a semicircular housing, which entirely covers the flexible ring F and the outer part of the ring D, while its inner part fits loose against the corresponding part of the ring D. Around the fold formed in the felt ring F is wound the cord d, one end of which is secured at e in the casing, opposite which point a part of the ring E is cut off, to allow for the passage of the opposite end of said cord d. This latter is tied to the upper end of the coil-spring f, the lower end of which has an eye to receive the hooked head of the threaded bolt g. A bracket, h, fastened at a proper angle on the outer face of the casing A, has a perforation 65 in its head to receive the threaded bolt g, which, by means of the nut i, can be adjusted so as to give to the cord d the degree of tension it requires.

Running through the open interior of the balloon B is the inverted trough H, the edges of which are fastened to the longitudinal bars h' h'. These bars are covered with felt or other suitable flexible material, to form a tight joint with the inner edge of the bars i' i' of the balloon B. The trough H is extended through the bearing-rings C D E into the suction-fan box I, wherein it is connected to the upper end of the flue J, the inner wall of which slopes inward below the said bearing-rings, so as to slide against the outer face of the casing A. Across this widened part of the flue J a pin, j, is set to receive the hooked upper end of the coil-spring k, the lower end of which is hooked to the head of the threaded bolt l. A bracket, m, suitably fastened to the casing A, has a perforation in its head to receive the lower end of the threaded bolt l, which, by means of the nut n, working on said bolt against the under face of the bracket m, is adapted to give to the packed edges of the inverted trough H the adjustment necessary to keep a perfectly air-tight joint between the same and the bars i' of the balloon. This will permit the air to pass through the sections of the balloon-cloth which happen to

be beneath the trough, and will thus allow of the freest play possible to the back draft or current induced in these sections of the cloth through the trough H and flue J. In order 5 to properly guide said flue, the pins e' e' are provided on the outer face of the ring E, between which its upper part is held in place. Though I have described only one flue, J, it must, however, be understood that each end 10 of the trough H is provided with one, both being attached in the same manner to the ends of the casing A, both ends of my machine being alike in every respect.

Having thus described my invention, what I 15 claim as new, and desire to secure by Letters Patent, is—

1. In a dust-collector, the combination, with the revolving balloon B and the casing A, of the rings C, D, E, and F, the cord d, coil-spring f, threaded bolt g, bracket h, and adjusting-nut i, substantially as shown and described, and for the purpose set forth.

2. In a dust-collector, in combination with the balloon B, casing A, and inverted trough 25 H, having longitudinal bars h' h', the flue J, having pin j, the coil-spring k, threaded bolt l, bracket m, and nut n, substantially as shown and described, and for the purpose set forth.

3. In a dust-collector, the combination, with 30 the balloon B, trough H, the flue J, fastening-pin j, spring k, bolt l, bracket m, and nut n, of the guide-pins e' e', held in the casing A, substantially as shown and described, and for the purpose set forth.

35 4. In a dust-collector, the combination, with a revolving balloon, a case inclosing the same, and metallic rings fastened to each of said parts and interposed between their respective

bearing-edges, of an annular band of felt or of any other flexible material interposed between 40 said metallic rings, and having one of its rims fastened to the case, while its other rim is suitably held against a projection of the ring of the balloon, so as to form an air-tight joint between the bearing parts, substantially as set 45 forth.

5. In a dust-collector, the combination, with a revolving balloon, a case inclosing the same, and metallic rings fastened to each of said parts and interposed between their respective 50 bearing-edges, of an annular band of felt or of any other flexible material interposed between said metallic rings, and having one of its rims fastened to the case, and an elastic binder adapted to keep the other rim of the annular 55 band in constant contact with the projecting periphery of the revolving balloon-ring, substantially as set forth.

6. In a dust-collector, the combination, with a revolving balloon, a case inclosing the same, 60 and an inverted trough held in the open center of said balloon, of a flue hung over each end of said trough, and connected to the sides of the case by an elastic binder, by means of which an air-tight joint is secured between the edges 65 of the trough and the balloon-bars, substantially as set forth.

In testimony that I claim the foregoing I have hereunto set my hand, at Milwaukee, in the county of Milwaukee and State of Wisconsin, in the presence of two witnesses.

WILLIAM RICHARDSON.
